(57) **CLAIM**

The ornamental design for a putter, as shown.

DESCRIPTION

FIG. 1 is a front perspective view of a putter;
FIG. 2 is a front elevation view of the putter of FIG. 1;
FIG. 3 is a first side elevation view of the putter of FIG. 1;
FIG. 4 is a second side elevation view, opposite the side
view of FIG. 3, of the putter of FIG. 1;
FIG. 5 is a rear elevation view of the putter of FIG. 1;
FIG. 6 is a top plan view of the putter of FIG. 1; and,
FIG. 7 is a bottom plan view of the putter of FIG. 1.
The broken line showing is for illustrative purposes only and
forms no part of the claimed design.
